(57) **CLAIM**

The ornamental design for a part of furniture element, as shown and described herein.

DESCRIPTION

FIG. 1 is a top, front, right side perspective view of our design for a part of furniture element.

FIG. 2 is a front view of the part of furniture element shown in FIG. 1.

FIG. 3 is a rear view of the part of furniture element shown in FIG. 1.

FIG. 4 is a right side view of the part of furniture element shown in FIG. 1.

FIG. 5 is a left side view of the part of furniture element shown in FIG. 1.

FIG. 6 is a top view of the part of furniture element shown in FIG. 1; and,

FIG. 7 is a bottom view of the part of furniture element shown in FIG. 1.

The appearance of any portion of the article between the break lines forms no part of the claimed design.
